UNITED STATES PATENT OFFICE.

GEORGE W. BARFIELD, OF ROME, GEORGIA.

CAR-COUPING.

SPECIFICATION forming part of Letters Patent No. 521,094, dated June 5, 1894.

Application filed January 9, 1894. Serial No. 496,224. (No model.)

To all whom it may concern:

Be it known that I, GEORGE W. BARFIELD, of Rome, in the county of Floyd and State of Georgia, have invented certain new and useful Improvements in Car-Couplings; and I do hereby declare the following to be a full, clear, and exact description of the invention, such as will enable others skilled in the art to which it appertains to make and use the same.

10 This invention relates to a new and improved car coupling and has reference more particularly to that class employing pivoted jaws or knuckles.

15 The object of the invention is, first, to provide a car-coupling with means for preventing accidents by reason of the pulling out or disconnecting of one drawhead; and, secondly, to provide an improved, simple and highly efficient form of drawhead and means for securing the same.

20 The invention comprises the details of construction, combination and arrangement of parts, substantially as hereinafter fully set forth and particularly pointed out in the 25 claims.

25 In the accompanying drawings:—Figure 1 is a plan view of my improved coupler. Fig. 2 is a view in side elevation. Fig. 3 is a front end view of the drawhead. Fig. 4 is an end 30 view of a car with my coupler attached. Figs. 5 and 6 are details.

35 Referring to the drawings, A designates the drawhead, having its outer end a curved and flared; and a' is the rearwardly projected chambered extension, the exterior of which is square, as at a², and cylindrical, as at a³. With the end of this chambered extension is formed, or it may be secured thereto, a key-plate B having a central and upper and lower 40 holes or openings b. Through these holes are passed draft-pins or headed rods b', the central one of which is inserted through the chambered extension. These draft-pins are also passed through a key-plate C having 45 holes or openings therein similar to key-plate B, and through slots in the projecting ends of said pins suitable keys are inserted. This arrangement constitutes a firm and secure lock for the drawhead.

50 D is the jaw or knuckle which is pivotally mounted between upper and lower horizontal ears d of one side of the flared end of the draw-

head, by a headed pin d' passed through coincident holes in said ears and center of jaw or knuckle. The inner end d² of this jaw or knuckle is bent or curved and designed to fit in a horizontal chamber d³ in the flared end of the drawhead. The outer end of this jaw or knuckle has a central horizontal slot d⁴, dividing said end into two corresponding ears d⁵, in holes in which latter a headed pin d⁶ is designed to fit for coupling a link to the jaw or knuckle. When the jaw or knuckle is closed the curved ends of ears d⁵ occupy a position corresponding to the curvature of the drawhead, leaving sufficient space for a correspondingly shaped jaw or knuckle to interlock therewith. The jaw or knuckle is held closed by a lock E movable in chamber d³. Said lock consists of a block e having a central rod e' extending therefrom upwardly through a hole in the top of the drawhead. When elevated the block e fits in a chambered extension of the top of the drawhead, the forward flanged end e² of said block 70 being designed to project into a recess e³. The block rests upon the inner curved end or tongue of the jaw or knuckle when the latter is opened. To the rod e' is connected a central arm f of a horizontal rod f' attached to 75 the end of a car, the ends of said rod having crank-handles whereby the lock can be raised from the sides of the car. For operating the same from the roof of a car a central vertical rod f² is connected to said rod e'. 85

F is a safety hook depending from the under side of the drawhead, its lower horizontal portion g being beneath the space between the jaw or knuckle and flared end of the drawhead, and is made sufficiently wide to 90 well extend over said space. The upper end g' of this hook is dovetailed and fits in a corresponding socket in the under side of the drawhead in which it is held by a nutted bolt g² passed through a hole therein and a hollow 95 web g³ extending downward from the drawhead. A central flange g⁴ projecting from the rear side of hook F bears at its upper edge against the under side of web g³, thus serving to additionally hold the hook F stationary. This safety hook is intended mainly to prevent injury to cars caused by a drawhead of either car being pulled out and falling beneath the rearward cars, which occasion dam- 100

age to the brake-rigging of such following cars, and in many cases causing the derailing of the latter. In the event of a drawhead pulling out the curved jaw or knuckle will fall down onto the safety hook of the other drawhead and be thereby prevented from falling to the ground. Should the drawhead of one car be higher or lower than another the safety hooks will overlap and serve as a support and additionally hold the couplers together.

In the event of breakage or damage to the safety hook the same can be readily removed and a new one substituted.

15 In cars having drawheads of unequal height the contact of the safety hooks serves to hold the couplers coupled when the train is traveling over rough tracks.

The advantages of my invention are apparent to those skilled in the art to which it appertains, and it will be specially observed that in addition to preventing accidents by falling drawheads, I provide simple and efficient means for securing the drawhead in place, and while I prefer to use three draft-pins or rods for this purpose I do not restrict myself thereto. Another advantage lies in the fact that with very slight attention my coupler can be attached to any and all cars now in general use.

I claim as my invention—

1. The combination with the drawhead having a dovetail slot in its under side, a rearward hollow web and a pivoted jaw or knuckle, of a hook having an upper dovetail end fitting said slot and provided with a hole or opening, and a nutted bolt passed through said hole and said hollow web, substantially as set forth.

2. The herein-described improved car coupling, comprising the drawhead having a rigid hook projecting from its under side and also provided with a forward flared end and a central chamber, a hollow rearward extension, two corresponding key-plates, draft-pins passed through holes in said key-plates, a jaw or knuckle pivoted to one side of said flared end and having a curved tongue movable in said chamber, the block fitted in said chamber for locking said tongue therein, the rod extending from said block, and means connected to said rod for operating said block from the sides or top of a car, substantially as set forth.

In testimony whereof I have signed this specification in the presence of two subscribing witnesses.

GEORGE W. BARFIELD.
